UNITED STATES PATENT OFFICE.

JOHN N. REYNOLDS, OF NEW YORK, N. Y., AND HENRY D. HILL, OF MONTCLAIR, NEW JERSEY, ASSIGNORS TO WESTERN ELECTRIC COMPANY, OF NEW YORK, N. Y., A CORPORATION OF ILLINOIS.

ELECTROMAGNET.

1,101,095.

Specification of Letters Patent. Patented June 23, 1914.

Application filed March 12, 1910. Serial No. 548,872.

To all whom it may concern:

Be it known that we, JOHN N. REYNOLDS and HENRY D. HILL, citizens of the United States, residing at New York, New York county, New York, and Montclair, Essex county, New Jersey, respectively, have invented a certain new and useful Improvement in Electromagnets, of which the following is a full, clear, concise, and exact description.

Our invention relates to electromagnets. Its object is to simplify and improve the structure of electromagnets, more particularly the structure of the armature and its support.

In the electromagnet of our invention the member which supports the armature is supplied with a portion extending away from the armature which provides a mounting for a flexible reed carrying the armature.

A further feature consists in cutting away a portion of the support opposite the reed, whereby a sharply defined bearing edge for said reed is provided. The edges of those portions of the armature members which embrace the reed will, in the ordinary process of manufacture, be sheared and therefore will be sharp and well defined. By cutting away the support, as described, the edges of the support will likewise be definite and the operative length of the reed can therefore be accurately gaged in assembling the parts.

Our invention, although capable of general application, is particularly adapted for use in bells and is herein illustrated by its embodiment in a bell of the reed or harmonic type commonly used in telephone systems.

Our invention will be more readily understood by reference to the accompanying drawings, in which--

Figure 1 is a front elevation of a telephone bell embodying our invention; Fig. 2 is a plan view of the armature, armature support, reed and a portion of the tapper arm, said members being shown removed from the associated parts of the electromagnet; Fig. 3 is a side elevation of the parts shown in Fig. 2; and Fig. 4 is a vertical sectional view on the line 4--4 of Fig. 2.

Referring to the drawings, Fig. 1 shows a bell of the general type known as "harmonic" comprising the electromagnet 4,

permanent magnet 5, gongs 6 and tapper arm 7. The support 8 for the armature may be mounted in any suitable manner. In the drawing the support is shown in threaded engagement with the core extensions 9, the construction employed being that wherein the cores of the electromagnet are rotatably carried within the spools of said electromagnet by the yoke 10, whereby they may be turned and thereby move the support 8 toward or from the cores as desired. 21 and 22 are lock nuts. The structure thus described, constituting no part of the present invention, is not set forth in detail.

Referring particularly to Figs. 2, 3 and 4, the support for the armature may consist of two members each of which comprises portion 11 and portion 12 extending away from the armature in substantially right angled relation to each other and a portion 13 joining said portions 11 and 12, whereby 70 said two members together constitute the support 8 having an arched portion. The two members may be so placed as to embrace the reed 14, said members being riveted or otherwise suitably secured together. The 80 armature may likewise consist of two members, each of said members comprising two substantially right angled portions 16 and 17. Said two members may be so placed as to embrace the reed 14, said members being riveted or otherwise suitably secured together. 85

With the form and arrangement of parts described the resulting structure is both simple and compact, the arched portions 13 90 forming a recess in which the reed 14 may lie and into which the projecting portions 17 of the armature may extend.

The support 8 may be formed with openings 18, whereby the portions 12, between which the reed is clamped, are provided with straight sharp edges 19, which definitely determine the line upon which the reed is clamped. It will be obvious that since the members of the support 8 would ordinarily 100 be stamped from sheet metal, the edges along the angles adjacent the reed would not be sharp unless made so by being dressed. By cutting away the metal opposite the reed to form the openings 18, as 105 described, the sharp edges 19 are provided for in the simple process of punching.

The members of the armature are formed

with straight edges 20 which sharply define the line on which the reed adjacent thereto is clamped.

With the construction described electro-
5 magnets may be readily manufactured hav-
ing reeds of uniform operative length, and
therefore uniform frequency, said lengths
being determined in assembling the struc-
ture by gaging the distance between the
10 edges 19 and 20.

It is evident that although in the struc-
ture shown herein the portion 13 joining the
portions 11 and 12 is straight, said portion
13 might be of curved form without exceed-
15 ing the scope of the invention.

Having described our invention, we claim:

1. The combination of an electromagnet,
an armature therefor, a support positioned
parallel to said armature and provided with
20 a portion extending away from the said
armature, and a reed securing the said arm-
ature to the said support portion.

2. The combination with an electromag-
net, of an armature, an arched support for
25 said armature, and a reed secured to said
armature and carried within the arched por-
tion of said support.

3. The combination with an electromag-
net, of an armature, an arched support for
30 said armature, a reed, and a projection from
said armature to which said reed is secured,
said projection extending into the arched
portion of said support.

4. The combination with an electromag-
net, of an armature, an arched support for
35 said armature, said armature and support
each comprising two members each member
having portions at right angles to each
other, and a reed for said armature carried
40 within the arched portion of said support.

5. The combination of an electromagnet,

an armature, a vibratory reed attached
thereto, and a support comprising members
clamping and carrying said reed, the mem-
bers having openings therein the edges of 45
the openings adjacent said reed forming a
sharply defined clamping line therefor.

6. The combination with an electromag-
net, of an armature, an arched support for
50 said armature comprising two members, and
a reed for said armature carried between
said members and within the arched por-
tion of said support, said support being cut
away opposite said reed to provide a sharply
55 defined bearing for said reed.

7. The combination with an electromag-
net, of an armature, an arched support for
50 said armature, said armature and support
each comprising two members having por-
tions at right angles to each other, and a
reed for said armature embraced by the
members of said armature and said support,
the legs of the arch of said support being
provided with openings adjacent the por-
tion of said reed located between the mem-
bers of said armature and said support, said
openings having sharply defined edges.

8. The combination of an electromagnet, a
pair of supporting members having open-
ings therein with sharply defined edges, a 70
reed clamped between said supporting mem-
bers adjacent to and extending beyond said
sharply defined edges, and an armature se-
cured to the extending end of said reed.

In witness whereof, we hereunto subscribe 75
our names this 9th day of March A. D.,
1910.

JOHN N. REYNOLDS.
HENRY D. HILL.
